UNITED STATES PATENT OFFICE

2,271,298

CONVERSION OF HYDROCARBON OILS

Lyman C. Huff, Chicago, Ill., assignor to Universal Oil Products Company, Chicago, Ill., a corporation of Delaware

Application August 28, 1937, Serial No. 161,402

8 Claims. (Cl. 196—48)

This is a continuation-in-part of my co-pending application Serial No. 113,424, filed November 30, 1936.

This invention relates to improvements in the type of process wherein hydrocarbon oils are pyrolytically converted to produce high yields of good antiknock gasoline and more specifically to a process wherein oils boiling above the range of gasoline are cracked to produce high yields of gasoline boiling range materials, the latter separated into light and heavy fractions and said heavy gasoline fractions reformed under cracking conditions of elevated temperature and superatmospheric pressure to materially improve their antiknock value.

One specific embodiment of the invention comprises cracking an oil of higher boiling characteristics than gasoline to produce therefrom high yields of gasoline boiling range materials, fractionating the resultant cracked vaporous products to separate therefrom, as reflux condensate, components boiling above the range of gasoline, returning said reflux condensate to further cracking within the system, further fractionating the uncondensed vapors, comprising predominantly materials within the boiling range of gasoline, to separate the same into low-boiling vaporous components comprising light gasoline fractions of satisfactory antiknock value and a higher boiling condensate comprising heavy gasoline fractions of unsatisfactory antiknock value, condensing and recovering said light gasoline fractions as a portion of the final motor fuel product of the process, subjecting said higher boiling condensate to cracking conditions of elevated temperature and superatmospheric pressure adequate to produce therefrom high yields of gasoline of improved antiknock value, separating vapors and non-vaporous residual components of the products of the last mentioned cracking operation, fractionating the last mentioned vapors out of contact with the vaporous products undergoing fractionation in the aforementioned fractionating steps to form another reflux condensate of higher boiling characteristics than gasoline, returning the latter to the first mentioned fractionating step and recovering from the fractionated vapors of the last described fractionating step a gasoline of better antiknock value and of wider boiling range than said heavy gasoline fractions subjected to the last mentioned cracking operation.

The present invention is not directed to any

specific single feature of the above described process but is believed to reside in the cooperative combination of features which result in the recovery, without further cracking, of those low-boiling gasoline fractions produced in the initial cracking operation which are of satisfactory antiknock value and further conversion of those higher boiling gasoline fractions produced in the initial cracking operation which are of unsatisfactory antiknock value to convert the same into high yields of a wider boiling range gasoline of materially improved antiknock value.

The invention also provides, as a special feature thereof, for the use, in addition to the charging stock supplied to the initial cracking operation, of a secondary charging stock such as gasoline or a distillate of substantially gasoline boiling range from an external source and which contains both low-boiling gasoline fractions of satisfactory antiknock value and higher boiling gasoline fractions of inferior antiknock value. This material may be supplied to the first or to the second mentioned fractionating step of the system and directly commingled therein with the vaporous conversion products of the process undergoing fractionation in this zone whereby its components of gasoline boiling range are separated, together with the gasoline conversion products of the initial cracking operation, into selected low-boiling and high-boiling fractions which are, respectively, recovered as a portion of the final motor fuel product and reformed or cracked to produce gasoline of improved antiknock value.

Another feature of the invention resides in the use of reflux condensate formed in the fractionating step of the reforming system as a heat exchange medium for reheating and/or reboiling the condensate supplied to said reforming step and/or as a cooling and fractionating medium in the initial fractionating step of the system.

The above mentioned and other features and advantages of the invention will be fully described and explained in conjunction with the following description of the accompanying dia-grammatic drawing. The drawing illustrates one specific form of apparatus in which the process of the invention may be successfully conducted to accomplish the desired results.

Referring to the drawing, heating coil 1, to which relatively heavy oil consisting predominantly of materials boiling above the range of gasoline is supplied, as will be later described, for cracking, is supplied with sufficient heat by means of furnace 2 to heat the oil passing

through the heating coil to the desired cracking temperature, preferably at a substantial superatmospheric pressure, and the heated products are directed from coil 1 through line 3 and valve 4 into reaction chamber 5.

Chamber 5 is also preferably maintained at a substantial superatmospheric pressure and, although not illustrated in the drawing, is preferably insulated to conserve heat so that the heated products supplied thereto, and particularly their vaporous components are afforded appreciable additional cracking in this zone. The resultant vaporous and liquid conversion products are withdrawn, in the particular case here illustrated, in commingled state from the lower portion of chamber 5 and directed therefrom through line 6 and valve 7 into vaporizing and separating chamber 8.

Chamber 8 is preferably operated at a substantially reduced pressure relative to that employed in the reaction chamber by means of which appreciable further vaporization of the liquid conversion products supplied thereto is accomplished. Separation of vapors and non-vaporous residue is accomplished in chamber 8 and, when this zone is operated for the production of liquid residue as a final product of the process, the latter may be removed from the lower portion thereof and directed through line 9 and valve 10 to cooling and storage or elsewhere, as desired.

The vaporous products are directed from the upper portion of chamber 8 through line 11 and valve 12 to fractionation in fractionator 13 wherein all or at least a major portion of their components boiling above the range of gasoline are condensed as reflux condensate. The total reflux condensate formed in fractionator 13 or selected high-boiling fractions thereof, as desired, are directed from the lower portion of this zone through line 14 and valve 15 to pump 16 by means of which they are supplied through line 17 and valve 18 to conversion, as previously described, in heating coil 1.

Although the invention is not so limited, it is ordinarily preferable to separate the reflux condensate formed in fractionator 13 into selected relatively low-boiling and high-boiling fractions, in which case only the high-boiling fractions are supplied, as previously described, to heating coil 1, while the lower boiling fractions may be recovered, all or in part, as a final product of the process, or preferably at least a portion thereof is subjected to further cracking within the system under cracking conditions controlled independently of those employed in heating coil 1. In the apparatus here illustrated, provision is therefore made for removing selected relatively low-boiling fractions of the reflux condensate from a suitable intermediate point in fractionator 13 and directing the same through line 19 and valve 20 to pump 21 by means of which they are supplied through line 22 and valve 23 to conversion in heating coil 24.

Furnace 25 supplies the required heat to the relatively low-boiling oil passing through heating coil 24 to heat the same to the desired cracking temperature, which is preferably somewhat higher than that employed in heating coil 1. A substantial superatmospheric pressure is also preferably maintained in heating coil 24 and a regulated portion or all of the highly heated products from this zone may be directed, when desired, through line 25 and valve 27 into reaction chamber 5 wherein they are further cracked in commingled state with the heated products

supplied to this zone, as previously described, from heating coil 1.

Fractionation may be so controlled in fractionator 13 that the resulting vaporous products which remain uncondensed in this zone consist substantially only of materials boiling within the range of gasoline and normally gaseous products, or, when desired, these vapors may include materials of a somewhat higher boiling nature than gasoline such as, for example, heavy naphtha fractions, kerosene, kerosene distillate, pressure distillate bottoms and the like. In the latter case, however, any such higher boiling fractions included with the vaporous product removed from fractionator 13, are of such a nature that they may be further cracked to produce additional yields of good antiknock gasoline under conditions suitable for reforming of the heavy gasoline components of the vapors to materially improve their antiknock value. These fractionated vaporous products are directed from the upper portion of fractionator 13 through line 30 and valve 31 to further fractionation in a secondary fractionator 32. The latter zone, as here illustrated, is a separate fractionating column, although it may, when desired, take the form of an extension to fractionator 13.

The vaporous products supplied to fractionator 32 are separated in this zone by fractional condensation into relatively low-boiling vaporous components, consisting of light gasoline fractions of satisfactory antiknock value and normally gaseous products, and a higher boiling condensate consisting of or containing at least a substantial quantity of heavy gasoline fractions of unsatisfactory antiknock value.

The low-boiling vapors which remain uncondensed in fractionator 32 are directed from the upper portion thereof through line 33 and valve 34 to condensation and cooling in condenser 35. The resulting distillate and uncondensed gases pass through line 36 and valve 37 to collection and separation in receiver 38. The uncondensed gases may be released from receiver 38 through line 39 and valve 40 to storage or elsewhere, as desired. Distillate collected in receiver 38 is withdrawn therefrom through line 41 and valve 42 to cooling and storage or to any desired further treatment and comprises the low-boiling gasoline fractions, produced as previously described, which are of satisfactory antiknock value.

When desired, regulated quantities of the distillate collected in receiver 38 may be returned therefrom to the upper portion of fractionator 32 as a cooling and refluxing medium by means of line 43, valve 44, pump 45, line 46 and valve 47. It is also within the scope of the invention to supply a suitable light distillate as a cooling and refluxing medium to the upper portion of fractionator 13, line 48 and valve 49 being provided in the case here illustrated for this purpose. The cooling and refluxing medium thus supplied to the upper portion of fractionator 13 may comprise, for example, distillate from receiver 38 or, preferably, a distillate resulting from total or partial condensation of a regulated portion of the normally liquid components in the vaporous stream removed from the upper portion of fractionator 13.

The condensate separated, as previously described, in fractionator 32 from the vaporous products supplied to this zone is removed from the lower portion thereof and directed through line 50 and valve 51 to pump 52 by means of

which it is supplied through line 54 to further cracking or reforming in heating coil 61, passing either through valve 55 in line 54 or, all or in part, through heat exchanger 58 by means of lines 56 and 59 controlled, respectively, by valves 51 and 60. The function of heat exchanger 58 will be later explained.

The heavy gasoline fractions or heavy-gasoline-containing condensate supplied to heating coil 61 is heated during its passage through this zone, by means of heat supplied from furnace 62, to cracking conditions of temperature and substantial superatmospheric pressure regulated to effect a material improvement in the antiknock value of said gasoline fractions and to produce additional yields of good quality gasoline from any higher boiling fractions of the condensate. The resulting highly heated products are discharged from heating coil 61 through line 63, which preferably contains a pressure control valve 64, and preferably after being partially cooled to a sufficiently low temperature to prevent any excessive further cracking thereof, are introduced into vaporizing and separating chamber 65. The desired cooling of these heated products is preferably accomplished, at least in part, by a substantial reduction in the pressure imposed thereon as they pass through valve 64. Any required additional cooling may be accomplished in any well known manner such as, for example, by indirect heat exchange with one or more relatively cool intermediate or final products of the process or charging stock therefor or by directly commingling a suitable cooling oil with the heated products passing through line 63. Means comprising lines 66 and valves 67, for introducing a suitable cooling oil into line 63 on either or both sides of valve 64, are shown in the drawing. The material thus utilized as a direct cooling medium may comprise, when desired, a relatively cool intermediate or final product of the process which will not contaminate the conversion products formed in heating coil 61 and which will not be readily reduced to coke or other objectionable products in line 63.

Undesirable high-boiling products such as heavy polymers and residual liquid are separated in chamber 65 from the vaporous components of the conversion products supplied to this zone and the heavy products thus separated from the vapors preferably include substantially all of the components of said conversion products which are not suitable for further cracking within the system to produce additional yields of gasoline. Preferably, controlled cooling is employed in the upper portion of chamber 65 to assist the desired separation of vaporous and heavy liquid products and means will be later described for supplying a suitable cooling medium to this point of the system.

In case chamber 65 is operated at a lower pressure or higher temperature, or both, relative to that employed in chamber 8 and it is desired to further vaporize and recover low-boiling fractions for further treatment from the residual liquid removed from chamber 8, the latter may be directed through line 68 and valve 69 into chamber 65 to undergo further vaporization and separation in this zone and it may be supplied either directly to chamber 65 at any desired point in this zone or may be introduced all or in part, by well known means, not illustrated, into line 63.

The heavy liquids which remain unvaporized in chamber 65 may be removed from the lower portion of this zone and directed through line 70 and valve 71 to cooling and storage or elsewhere, as

desired. The vaporous products from chamber 65 are directed therefrom to fractionation in fractionator 72 wherein their components boiling above the range of the desired gasoline product of this stage of the system are condensed as reflux condensate.

Fractionated vapors of the desired end-boiling point, which remain uncondensed in fractionator 72, comprise the normally gaseous products of this stage of the process and gasoline of good antiknock value, the latter preferably being of higher end-boiling point than that recovered from receiver 38. These vapors are directed from the upper portion of fractionator 72 through line 73 and valve 74 to condensation and cooling in condenser 75. The resulting distillate and uncondensed gases pass through line 76 and valve 77 to collection and separation in receiver 78. The uncondensed gases are released from the receiver to storage or elsewhere, as desired, through line 79 and valve 80. Distillate is withdrawn from receiver 78 through line 81 and valve 82 to storage or to any desired further treatment. Regulated quantities of the distillate collected in receiver 78 may be recirculated by means of line 83, valve 84, pump 85, line 86 and valve 87 to the upper portion of fractionator 72 as a cooling and refluxing medium.

The reflux condensate formed in fractionator 72 is removed from the lower portion of this zone through line 90 and valve 91 to pump 92 by means of which it is fed through line 93 and may be directed all or in part, when desired, through line 94, valve 95, line 101, valve 102 and line 108 into fractionator 13 at any desired point in this zone wherein it commingles with the vaporous products undergoing fractionation therein, serves as a cooling and refluxing medium for the vapors and is at least partially vaporized and subjected to fractionation therewith. Preferably, however, useful heat is extracted from the reflux condensate formed in fractionator 72 to preheat and/or reboil the condensate supplied from fractionator 32 to heating coil 61. Preheating of said condensate from fractionator 32 may be accomplished by passing all or a regulated portion of the reflux condensate from fractionator 72 through valve 96 in line 93 into and through heat exchanger 58 in indirect heat exchange with the condensate from fractionator 32 and thence through line 97 and valve 98 into line 101. Reboiling of the condensate formed in fractionator 32, whereby to substantially free the same of dissolved gases and other undesired low-boiling components, may be accomplished by diverting regulated quantities of the reflux condensate from line 102 through line 103 and valve 104 into and through a suitable closed coil or heat exchanger 105 in indirect heat exchange with the condensate in the lower portion of fractionator 32 and thence through line 106 and valve 107 into line 108. This reboiling may, when desired, be accomplished in a zone of any well known form, not illustrated, external to fractionator 32 wherefrom the light fractions evolved from the condensate may be returned to fractionator 32 or to condenser 35.

When heat is extracted from the reflux condensate formed in fractionator 72 in either or both of the manners described, it not only serves the useful purpose mentioned of preheating and/or reboiling the condensate from fractionator 72, but will also function as a more efficient cooling and refluxing medium in fractionator 13.

The invention also contemplates the use of

regulated quantities of the reflux condensate formed in fractionator 72 as a cooling and refluxing medium in the upper portion of chamber 65. This is accomplished in the case here illustrated by diverting regulated quantities of the reflux condensate from line 101, through line 109, valve 110, cooler 111, line 112 and valve 113 into the upper portion of chamber 65 wherein it preferably is intimately contacted by means of a suitable spray, baffles, perforated pans, bubble trays or the like, not illustrated, with the vaporous products in this zone of the system, serving to partially cool the same and remove undesirable high-boiling components therefrom, so that only relatively clean vapors suitable for further cracking in heating coil 24 and/or 1 are supplied from chamber 65 to fractionator 72.

Reflux condensate from fractionator 72 may also be introduced into line 63, by well known means, not illustrated, through one or both of the lines 66 and valves 67, to serve as a cooling medium for the hot conversion products discharged from heating coil 61 prior to its introduction into chamber 65 and, when reflux condensate from fractionator 72 is thus utilized, it may be supplied to line 63 directly from pump 92 or from heat exchanger 58 or from cooler 111 or a similar cooler, by well known means, not illustrated.

When heating coil 24 is utilized, the invention also contemplates the introduction, when desired, of a regulated portion or all of the highly heated products from this zone, with or without prior cooling to any desired degree, into chamber 65 instead of into reaction chamber 5. Provision is made in the case here illustrated for diverting regulated quantities of these products from line 26 through line 114 and valve 115 into line 63 and thence to chamber 65, although products from heating coil 24 may be separately supplied, with or without prior cooling, to chamber 65 at any desired point in this zone, by well known means, not illustrated.

Charging stock for the process is supplied through line 116 and valve 117 to pump 118 by means of which it is directed in any one or any desired combination of several alternative but non-equivalent manners of treatment within the system. The point or points at which the charging stock is introduced into the system may be selected to suit the type of charging stock employed. In case it is an oil of relatively wide boiling range, such as crude petroleum, topped crude or the like, containing a substantial quantity of both relatively low-boiling and high-boiling components, and in case heating coil 24 is employed, the charging stock is preferably directed from pump 118 through line 119 and valve 120 into fractionator 13, wherein it commingles with the relatively hot vaporous conversion products undergoing fractionation in this zone and is separated therewith into relatively low-boiling and high-boiling fractions for treatment in the respective heating coils 24 and 1. The charging stock is also preferably supplied to fractionator 13 in case it contains any low-boiling gasoline fractions of satisfactory antiknock value, so that the latter may be vaporized in fractionator 13 and recovered as a portion of the overhead product from fractionator 32. The charging stock may be supplied to fractionator 13 in any case except when it contains low-boiling fractions which would contaminate the overhead product from fractionator 32 if commingled therewith and, in any case, may, when desired, be preheated

to below cracking temperature by any well known means, not illustrated, prior to its introduction into the fractionator. However, in case the charging stock is an oil of relatively high-boiling

characteristics, or in case heating coil 24 is not employed, it may be supplied all or in part directly to heating coil 1 by means of lines 121, 122, 123, valve 124 and line 17. When heating coil 24 is employed and the charging stock is an oil of relatively low-boiling characteristics suitable for cracking in this zone, it may be supplied all or in part directly to heating coil 24 by means of valve 125 in line 122 and line 22. In case the charging stock does not contain materials of unsatisfactory antiknock value which boil within the range of the reformed gasoline product, it may be supplied all or in part by means of valve 126 in line 121 to fractionator 72 to commingle therein with the vaporous products undergoing fractionation in this zone, assisting their fractionation and being subjected to fractionation therewith. In the latter case the total charging stock, or high-boiling components thereof which remain unvaporized or are condensed in fractionator 72, are supplied therefrom, together with the reflux condensate formed in this zone, to fractionator 13, in the manner previously described, and thence to cracking in heating coil 24 and/or heating coil 1.

The process herein disclosed is well adapted to the treatment of a secondary charging stock which may comprise distillate such as straight-run gasoline, pressure distillate or cracked gasoline from another cracking operation or any other relatively low-boiling oil consisting primarily of gasoline boiling range materials and containing both low-boiling gasoline fractions of satisfactory antiknock value and higher boiling gasoline fractions of unsatisfactory antiknock value. Provision is made in the case here illustrated for supplying such secondary charging stock through line 127 and valve 128 to pump 129 by means of which it is fed through line 130 and may be introduced all or in part through line 132 and valve 133 directly into fractionator 13, wherein it commingles with the hot vaporous conversion products undergoing fractionation and is substantially vaporized, the vaporized gasoline components passing from fractionator 13, together with the cracked gasoline vapors from this zone of the system, through line 30 and valve 31 to further fractionation, as previously described, in fractionator 32. Provision is also made in the case here illustrated for preheating the secondary charging stock prior to commingling the same with the vaporous conversion products undergoing fractionation by directing the same through valve 131 in line 130 into and through heat exchanger 134, wherein it passes in indirect heat exchange with the relatively hot vaporous conversion products undergoing fractionation in fractionator 13 and wherefrom it may be thence directed through line 135 and valve 136 directly into fractionator 13 at a point beneath heat exchanger 134. In case the secondary charging stock does not contain any appreciable quantity of materials boiling substantially above the range of gasoline and in case any such high-boiling components thereof are suitable for cracking in heating coil 61, together with the high-boiling gasoline fractions supplied to this zone, to produce additional yields of good quality gasoline, all or a regulated quantity of the secondary charging stock may be supplied to fractionator 32. In the latter case, the secondary charging stock is preferably preheated prior

to being commingled with the vaporous products undergoing fractionation in fractionator 32 and provision is made in the drawing for directing preheated secondary charging stock from heat exchanger 134 through line 135, line 137, valve 138 and line 30 into fractionator 32.

In addition to the provisions previously described for partially cooling relatively hot conversion products at various points in the system, the invention contemplates partially cooling the heated products supplied from chamber 5 to chamber 8, to arrest or retard their further cracking, by commingling a suitable cooling oil therewith in line 6 on either or both sides of the pressure reducing valve 7, lines 140 containing control valves 141 being provided for this purpose. Provision is also made for utilizing a suitable cooling and refluxing medium in the upper portion of chamber 8 and line 142 controlled by valve 143 is provided for the introduction of a suitable cooling and refluxing medium into this zone. The cooling medium thus utilized in line 6 and/or the upper portion of chamber 8 may comprise, for example, regulated quantities of all or a selected fraction of the reflux condensate formed in fractionator 13, or the reflux condensate formed in fractionator 72, or regulated quantities of the charging stock supplied to the system.

The preferred range of operating conditions which may be employed within the scope of the invention, to accomplish the desired results in an apparatus such as illustrated and above described, may be approximately as follows: Heating coil 1 may employ a conversion temperature, measured at the outlet therefrom, ranging, for example, from 850 to 950° F., or thereabouts, preferably with a superatmospheric pressure at this point in the system of from 100 to 500 pounds, or thereabouts, per square inch. Heating coil 24, when utilized, preferably employs a higher cracking temperature than heating coil 1, the preferred range, as measured at the outlet of heating coil 24, being from 900 to 1000° F., or more, preferably with a superatmospheric pressure at this point in the system of from 200 to 800 pounds, or thereabouts, per square inch. Any desired superatmospheric pressure no greater than that employed at the outlet of the communicating heating coil utilizing the lowest pressure may be employed in reaction chamber 5, the preferred range being from 100 to 500 pounds, or thereabouts, per square inch. Vaporizing and separating chamber 8 is preferably maintained at substantially reduced pressure relative to that employed in chamber 5, said reduced pressure ranging, for example, from 150 to 25 pounds per square inch, superatmospheric. Fractionators 13, 32 and the communicating condensing and collecting equipment may employ pressures substantially the same or somewhat lower than that utilized in chamber 8, fractionator 32 being operated, when desired, at an appreciably lower pressure than that employed in fractionator 13. Heating coil 61 preferably employs an outlet temperature within the range of 925 to 1050° F. or more, preferably with a superatmospheric pressure at this point in the system which may range as high as 1000 pounds, or more, per square inch. The products supplied from heating coil 24 and/or heating coil 61 to chamber 65 are preferably cooled to a temperature of the order of 600 to 800° F., prior to their introduction into this zone, and their vaporous components may be further

cooled within chamber 65. When residual liquid from chamber 8 is supplied to chamber 65 the latter zone is preferably operated at a lower pressure or higher temperature, or both, with respect to the temperature and pressure conditions employed in vaporizing and separating chamber 8. The pressure employed in chamber 65, which is preferably of the order of 100 pounds or more per square inch, superatmospheric, down to substantially atmospheric pressure, may be substantially equalized or reduced in the succeeding fractionating, condensing and collecting equipment.

As a specific example of an operation of the process as it may be conducted in an apparatus of the character illustrated and above described: The charging stock is a Montana crude of about 32° A. P. I. gravity which contains approximately 26% of straight-run gasoline boiling up to 437° F. The charging stock is supplied to fractionator 13 wherein it is separated, together with the vaporous conversion products supplied to this zone, into an overhead vaporous fraction having an end-boiling point of approximately 550° F., an intermediate fraction having an initial boiling point of approximately 300° F. and an end-point of approximately 630° F. and a heavy liquid fraction having an initial boiling point of approximately 320° F. and containing approximately 35% of material boiling up to 600° F. Said high-boiling fraction is heated in heating coil 1 to an outlet temperature of approximately 910° F. at a superatmospheric pressure of approximately 300 pounds per square inch. The intermediate liquid fraction is supplied to heating coil 24 wherein it is heated to a cracking temperature of approximately 950° F. at a superatmospheric pressure of approximately 350 pounds per square inch. The hot conversion products from heating coils 1 and 24 are supplied to reaction chamber 5 which is maintained at a superatmospheric pressure of approximately 300 pounds per square inch. Vaporizing and separating chamber 8, to which the total vaporous and liquid products from chamber 5 are supplied in commingled state, is maintained at a superatmospheric pressure of approximately 120 pounds per square inch, residual liquid from this zone being supplied to chamber 65, while the vaporous products are directed to fractionator 13. The overhead vaporous stream from fractionator 13 is supplied to secondary fractionator 32 and a secondary charging stock, comprising pressure distillate from an external source having an initial boiling point of approximately 90° F. and an end-boiling point of approximately 560° F., is also introduced into fractionator 32 after being first preheated, by indirect heat exchange with the vaporous products undergoing fractionation in fractionator 13, to a temperature of approximately 400° F. The overhead vaporous product from fractionator 32 has an end-boiling point of approximately 370° F. and a light gasoline of approximately this end-point is condensed and separated from the normally gaseous products. The bottoms removed from fractionator 32 have an initial boiling point of approximately 240° F. and an end-boiling point of approximately 560° F. This material is subjected in heating coil 61 to a conversion temperature of approximately 980° F. at a superatmospheric pressure of about 400 pounds per square inch, as measured at the outlet from heating coil 61. These products are cooled to a temperature of approximately 675° F., prior to their introduction into chamber 65, and

are further cooled in chamber 65 by cooling and recirculating reflux condensate from fractionator 32 to the upper portion of this zone. A reformed gasoline of approximately 400° F. end-boiling point is recovered from fractionator 72 as the overhead product and residual liquid is recovered from the lower portion of chamber 65. Reflux condensate formed in fractionator 72, which has an initial boiling point of approximately 375° F. and an end-boiling point of approximately 650° F., is in part cooled and returned to the upper portion of chamber 65, while the remainder is utilized as a reboiling medium for the bottoms from fractionator 32 and is thence introduced into fractionator 13.

The above described operation will yield, per barrel of total charging stock (which consists of approximately 70% crude oil and approximately 30% pressure distillate), approximately 75% of gasoline having an antiknock value of better than 70 by the motor method and approximately 14% of heavy fuel oil recovered as residue from chamber 65, the remainder being chargeable principally to uncondensable gases.

I claim as my invention:

1. A process for the pyrolytic conversion of hydrocarbon oils which comprises cracking an oil of higher boiling characteristics than gasoline at substantial super-atmospheric pressure in a heating coil and separating the resulting vaporous and liquid conversion products, fractionating the vaporous conversion products, to condense therefrom as reflux condensate components boiling above the range of gasoline, supplying reflux condensate formed by said fractionation to the heating coil for cracking therein, subjecting resultant fractionated vapors to further fractionation in a second fractionating step and commingling with the vapors supplied to said second fractionating step distillate from an external source which contains at least a substantial quantity of low-boiling gasoline fractions of good antiknock value and a substantial quantity of higher boiling gasoline fractions of inferior antiknock value, separating the commingled materials in said second fractionating step into low-boiling vaporous components consisting predominantly of light gasoline fractions of satisfactory antiknock value and a higher boiling condensate comprising low antiknock high-boiling gasoline fractions of said distillate and of the cracked vapors, subjecting said low-boiling vaporous components to condensation and recovering and separating the resulting light gasoline distillate and uncondensed gases, reforming said higher boiling condensate formed in the second fractionating step to produce therefrom high yields of good antiknock gasoline by heating the same to a high cracking temperature at substantial superatmospheric pressure in a separate heating coil, partially cooling the resulting highly heated products and separating the partially cooled materials into vapors and heavy non-vaporous components, fractionating the last named vapors out of contact with the vaporous products in the aforementioned fractionating steps to condense therefrom as reflux condensate components boiling above the range of the desired reformed gasoline product, passing reflux condensate formed in the last described fractionating step in direct heat exchange with said higher boiling condensate prior to the reforming of the latter and then returning the reflux condensate to the first mentioned fractionating step in liquid form to serve as a refluxing medium in said first-mentioned

fractionating step, and subjecting fractionated vapors of the desired end-boiling point from the last described fractionating step to condensation to recover therefrom a reformed gasoline of good 5 antiknock value and of higher end-boiling point than said gasoline distillate recovered from the second mentioned fractionating step.

2. A process such as defined in claim 1 wherein said distillate from an external source is 10 passed in indirect heat exchange with the vaporous products undergoing fractionation in the first mentioned fractionating step prior to commingling with the vaporous products subjected to said further fractionation in the second fractionating step.

3. A process such as defined in claim 1 wherein said distillate from an external source is partially vaporized by passing the same in indirect heat exchange with the vaporous products undergoing fractionation in the first mentioned fractionating step, the resulting heated and partially vaporized distillate thence directly commingled with the vaporous products in the first mentioned fractionating step and only its 20 resultant vaporized components subjected to further fractionation in the second fractionating step.

4. A process such as defined in claim 1 wherein in regulated quantities of the reflux condensate 30 formed in the last described fractionating step are cooled and thence commingled with relatively hot products of the reforming step to assist said partial cooling and separation thereof.

5. A process such as defined in claim 1 wherein 35 in regulated quantities of the reflux condensate formed in the last described fractionating step are cooled and commingled with vaporous products of the reforming step prior to said fractionation of the latter.

6. A conversion process which comprises cracking hydrocarbon oil heavier than gasoline, and separating resultant vapors from residue, fractionating the vapors to separate therefrom a reflux condensate heavier than gasoline, a light 40 gasoline vapor and an intermediate condensate containing the heavy gasoline fractions, returning said reflux condensate to the cracking operation, finally condensing and collecting said light gasoline vapor, reforming said intermediate condensate by subjection to cracking conditions independently of the first-mentioned oil, fractionating the vaporous products of the reforming step independently of the first-named vapors, passing resultant reflux condensate in indirect 45 heat exchange with said intermediate condensate prior to supplying the latter to the reforming step, then introducing the last-mentioned reflux condensate into contact with the first-named vapors undergoing fractionation to serve 50 as a refluxing medium for these vapors, and finally condensing the vapors uncondensed by the fractionation of said vaporous products of the reforming step.

7. A conversion process which comprises 55 cracking hydrocarbon oil heavier than gasoline, fractionating the resultant vapors to condense fractions thereof heavier than gasoline and returning fractions so condensed to further cracking within the system, further fractionating the vapors to separate the same into light gasoline fractions of satisfactory anti-knock value and a higher boiling condensate comprising low antiknock heavy gasoline fractions, condensing and recovering said light gasoline fractions, subjecting 60 said condensate to reforming to increase the 70

75

anti-knock value of said heavy gasoline fractions, fractionating the vaporous products of the reforming step independently of the first-mentioned vapors, passing resultant reflux condensate in indirect heat exchange with said higher boiling condensate being supplied from the second-mentioned fractionating step to the reforming step, then returning the reflux condensate to the first-mentioned fractionating step in liquid form to serve as a refluxing medium in said first-mentioned fractionating step, and condensing

and collecting the reformed vaporous products uncondensed in the third-mentioned fractionating step.

8. The process as defined in claim 7 further characterized in that said higher boiling condensate is reboiled during its indirect heat exchange with said reflux condensate to free it of good anti-knock low-boiling gasoline fractions prior to the reforming thereof.
